UNITED STATES PATENT OFFICE

2,225,049

WOODWORKING TOOL

Theron L. Hedgpeth, Oak Park, Ill., assignor to
Duro Metal Products Company, Chicago, Ill.,
a corporation of Illinois

Application February 27, 1939, Serial No. 258,670

2 Claims. (Cl. 144—253)

The present invention relates to woodworking tools, and is particularly concerned with improvements in jointers. jointer other than that disclosed therein may be substantially as disclosed in my prior patent, No. 2,123,627, which includes a base 19 provided with a pair of bearings for rotatably supporting a cut-

This application relates to improvements in suitable bearings for rotatably supporting a cutter shaft 20, bearing the cutter 21, provided with blades 22, and bearing at its opposite end a

One of the objects of the invention is the provision of an improved jointer structure, including manual means for the adjustment of the bearing plate upon which the work fence is mounted so that the position of the work fence may be quickly and conveniently adjusted to the drive pulley 23. The base 19 has the diagonally extending guide 24 for adjustably supporting the two table sections 25 and 26, and the right-hand table section 26 is adapted to support the work fence 21 and its associated adjusting mechanism.

Another object of the invention is the provision of an improved jointer having locking means for maintaining the work fence in horizontal position, and having an improved structure permitting the pivotal movement of the work fence about a vertical axis. Referring to Fig. 5, the table section 26 preferably has its rear wall 28 provided with a cylindrical bore 29 for receiving a supporting shaft 30. The rear wall 28 has an inwardly extending tubular formation 31 for increasing the length of the bore 29; and the shaft 30 may be secured in the bore 29 by means of a set screw 32.

20 Another object of the invention is the provision of an improved fence bearing plate structure which is adapted to act as an auxiliary blade guard when the fence has been moved forwardly. threaded into the tubular formation 31. The shaft 30 is thus fixedly supported on the table section 26, and it extends rearwardly of the table in a horizontal direction, and is provided on its one side with gear teeth, forming a rack 25

25 Another object of the invention is the provision of an improved support for a work fence for a jointer or similar tool, which is sturdy, capable of economical manufacture, and simple, so that adjustments may be made quickly and 33, and in its upper side with a substantially V-shaped groove 34.

The work fence 27 may be constructed of sheet metal, having a flat rectangular body portion 35, which is provided with a rearwardly extending border flange 36 at the top and a bor- 30

30 the fence quickly secured in any desired position. Extending border flange 30 at the top and 31 at the bottom, the upper end of which is beveled upwardly at 32 each border flange 31 at each end. The lower end of 33 which is beveled upwardly at 34 each border flange 31 is beveled upwardly at 35 36 which similar characters of reference indicate fence 27 while still keeping the lower edge 39 of 37 similar parts throughout the several views. 38 the work fence close to the table top or in em- 39

Referring to the drawings, of which there are **40** engagement therewith.
three sheets: A longitudinally extending angle member **40**

Fig. 1 is a top plan view of a jointer constructed according to the invention; Fig. 2 is a fragmentary vertical elevational view of the sheet metal work fence.

The work fence is provided with a pair of pivot brackets 41, 42, which are identical in structure,

Fig. 3 is a fragmentary vertical elevational view, taken from the left of Fig. 1; Fig. 4 is a fragmentary rear elevational view, taken from the top of Fig. 1;

45 taken from the top of Fig. 1; Fig. 5 is a fragmentary vertical sectional view, taken on the plane of the line 5-5 of Fig. 1, looking in the direction of the arrows;

Fig. 7 is a fragmentary vertical sectional view, taken on the plane of the line 7—7 of Fig. 1, looking in the direction of the arrows. The figures for receiving the screw bolts 46, 47, which also pass through apertures in the parallelogram links 48, 49, whereby the parallelogram links

Referring to Figs. 1 to 4, the structure of the *l* are pivotally mounted on the bolts 46, 47. The

parallelogram links 48, 49 may comprise elongated cast metal members formed with hubs at each end.

The work fence and its associated mechanism 5 are all supported upon a pivotally mounted fixture 50, which may be made of cast metal, and which has a substantially horizontal body flange 51. The body flange 51 may comprise a member which is formed with a substantially circular boundary 52 at its rear edge, and which has an elongated front portion 53 of sufficient length to span the space between the brackets 41 and 42.

The circular portion 52 is provided with a centrally located cylindrical bore 54, and the lower side of the body flange 51 has an annular engaging rib 55. At its front the elongated body portion 53 may be provided with an upwardly turned flange 56, which is joined at each end to the body 20 by webs 57 for reinforcement.

The upwardly extending flange 56 and web 57 support a pair of parallel substantially cylindrical bearing discs 58, 59. The bearing discs 58, 59 are provided with centrally located apertures 60 for receiving an adjustment shaft 61. The adjustment shaft 61 is rotatably mounted in the bearings 60, and at each end it carries a disc-shaped member 62, 63, which is secured to the shaft by means of set screws or other convenient securing means.

The discs 62, 63 are provided with threaded apertures for receiving the ends of the screw bolts 64, 65, 66, 67, which pass through apertures at the ends of the parallel links 48, 49 at each end 35 of the work fence. The apertures in the discs 62, 63 are preferably oppositely located on the same diameter so that the links 48, 49 and the lines of centers between the bolts 46, 47 and 66, 67 describe a parallelogram.

40 The vertical angularity of the work fence 27 may thus be adjusted by rotating the discs 62, 63 and shaft 61. For this purpose the work fence itself may be grasped and its angle changed, assuming that the clamping devices, further to be 45 described, are loosened.

In order to clamp the links in predetermined position, the screw bolts 64 and 66 are provided with hand knobs 68, 69, which are used to clamp the uppermost links 48 tightly against the discs 50 62, 63 to hold the linkage in fixed position. When this is done, the complete assembly, comprising the work fence 27, links 48, 49, discs 62, 63, and shaft 61 may still rotate as an entirety on the shaft 61 and means is provided for preventing 55 this rotation, comprising a threaded member 70, provided with a hand knob 71. This threaded member 70 is shown in Fig. 7, where it is threaded into a threaded bore 72 in such manner that 60 the end of the threaded member 70 may engage and clamp the shaft 61.

The fixture 50, which supports the fence 27 and associated mechanism, is itself rotatably supported on a slider 73 (Fig. 5), which may be 65 made of cast metal. The slider 73 is provided with a horizontal bore 75, which has a clearance at 76. This may be accomplished by casting the fixture 73 with bores 75 slightly smaller than the desired size, and machining out the bores 75 to 70 an accurate fit of the shaft 30.

The fixture 73 also has an upwardly extending column surrounded by a horizontal, circular plate 77 for engaging the under side of the fixture 50. The plate 77 is supported by the column 78, which 75 has a reinforcing rib 79, and the plate and col-

umn are provided with a threaded bore 80 and threaded counterbore 81.

The fixture 50 is rotatably supported upon the plate 77 by means of a tubular threaded member 82, having a radially extending flange or head 5 83 at the top for engaging the washer 84 and holding the fixture 50 against the plate 77.

The tubular member 82 has an axial bore 85 and external threads at 86 for engaging in the threaded bore 80. Thus the tubular member 82 10 15 may be driven into its bore 80 in the slider 73 until the fixture 50 is supported for rotation on a vertical axis, so that the work fence 27 may be located parallel to the edges of the table sections or diagonally thereto.

Furthermore, the threaded tubular member 82 may be driven down into its threaded bore 80 until the fence is clamped in any desired position, longitudinally or transversely of the table sections.

20 The threaded bore 81 in the slider 73 is adapted to receive the screw bolt 87, which has a conical end 88, adapted to be slidably received in the V-shaped groove 34 of the guide shaft 30. By means of the head of the bolt 87, this bolt may be 25 driven down into its threaded bore 81 until the slider 73 is merely guided for sliding movement on the shaft 30, but rotation on the shaft 30 is prevented. By driving the bolt 87 down tightly into the groove 34, the slider 73 may be clamped 30 in any desired longitudinal position on the guide shaft 30.

The two threaded members 87 and 82 are peculiarly adapted to be actuated by the same end of a wrench, which has a pair of suitable 35 sockets, one of which is adapted to fit the head of the bolt 87, and the other side of the same socket adapted to fit the head of the threaded member 82, which preferably has a hexagonal head also.

40 The sliding member 73 is adapted to be directed or actuated in its sliding movement by means of the rack 33 and the pinion 89 (Fig. 4). For this purpose the slider 73 has a transverse enlargement 90, which is provided with a vertically extending bore 91 and counterbore 92. The counterbore 92 is adapted to serve as a bearing for the drive shaft 93, which extends through the counterbore 92 into the bore 91.

The drive shaft 93 is provided at the top with 50 a hand knob 94, and the two plates 51 and 77 are provided with arcuate slots 95 for passing the drive shaft 93, so that it may project from the top of the mechanism for adjustment.

At its lower end the drive shaft 93 is provided 55 with the pinion 89, which may be formed with the gear teeth 96 at its upper end, and at its lower end with a radially projecting flange 97, adapted to serve as a thrust bearing.

The pinion 89 has a longitudinally extending bore 98, which is adapted to receive the shaft 93, and the pinion may be secured to rotate with the shaft by means of a set screw 99, preferably of the hexagonal socket type. Above the enlargement 90 of the slider 73, the shaft 93 may be provided with a thrust bearing 100, comprising a metal collar fitting on the shaft 93 and having a suitable set screw 101.

70 Referring to Fig. 3, it will be observed that the rack 33 on the guide shaft 30 does not extend to the extreme end 102 of that shaft, but terminates at the point 103. This acts as a stop surface in cooperation with the teeth of the pinion 96, as the fixture can be moved outward no farther 75

after the teeth of the pinion 89 engage the cylindrical end portion of the shaft at 103.

It will thus be observed that the fence and its associated mechanism carried by the slider 73 may be moved forward and backward by means of the rotation of the knob 94, which actuates pinion 89 on rack 33. It may be clamped in place by driving the screw bolt 87 home.

The lower edge 39 of the fence 27 may be provided with a shallow, arcuate groove 104 so located that the fence has a clearance with respect to the cutter 22 when the fence is resting on the table top in such a position as to be above the cutter.

Due to this arrangement the fence 27 may be moved forward by means of the rack and pinion until it covers all of the cutter which is not being used, and only that portion of the cutter which is exposed in front of the fence may be used.

The fence is thus adapted to serve as an auxiliary blade guard when it is in this forward position.

The work fence is adapted to be so adjusted that it may rest upon the table sections 25 or 26, to be elevated by the elevation of either section, or it may be clamped at any elevation by means of the threaded member 10 and the knobs 68, 69.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a woodworking tool, the combination of a work support with a cutter carried by said support mounted on a shaft, said support having a pair of work tables mounted thereon for adjustment at any of a plurality of elevations with regard to said cutter, a laterally extending shaft carried by said support, said shaft having a pair of longitudinally extending guide surfaces, a fixture slidably mounted on said shaft, said shaft having a rack formed on one side thereof, a pinion carried by a second shaft rotatably mounted on said fixture, said pinion engaging said rack, said second shaft having a hand wheel for actuation of said pinion, said fixture being provided with a horizontal face flange, a work fence supporting member having a similar horizontal face

flange, said latter member and fixture having registering centrally located bores, a headed member extending through said supporting member and threaded into said fixture, said headed member having a centrally located bore, and a bolt threaded into said fixture and extending through said headed member, and having its non-circular head projecting therefrom for engagement with a tool, said bolt having its end formed with surfaces complementary to said guide surfaces whereby the fixture may be slidably mounted on said first-mentioned shaft and clamped in predetermined position by said bolt.

2. In a woodworking tool, the combination of a work support with a cutter carried by said support mounted on a shaft, said support having a pair of work tables mounted thereon for adjustment at any of a plurality of elevations with regard to said cutter, a laterally extending shaft carried by said support, said shaft having a pair of longitudinally extending guide surfaces, a fixture slidably mounted on said shaft, said shaft having a rack formed on one side thereof, a pinion carried by a second shaft rotatably mounted on said fixture, said pinion engaging said rack, said second shaft having a hand wheel for actuation of said pinion, said fixture being provided with a horizontal face flange, a work fence supporting member having a similar horizontal face flange, said latter member and fixture having registering centrally located bores, a headed member extending through said supporting member and threaded into said fixture, said headed member having a centrally located bore, and a bolt threaded into said fixture and extending through said headed member, and having its non-circular head projecting therefrom for engagement with a tool, said bolt having its end formed with surfaces complementary to said guide surfaces whereby the fixture may be slidably mounted on said first-mentioned shaft and clamped in predetermined position by said bolt, 35
